FIG. 1

UNITED STATES PATENT OFFICE.

WILLIAM F. HELMOND, OF HARTFORD, CONNECTICUT, ASSIGNOR TO UNDERWOOD TYPE-WRITER COMPANY, OF NEW YORK, N. Y., A CORPORATION OF DELAWARE.

TYPE-WRITING MACHINE.

1,223,279.

Specification of Letters Patent. Patented Apr. 17, 1917.

Application filed July 26, 1915. Serial No. 41,870.

To all whom it may concern:

Be it known that I, WILLIAM F. HELMOND, a citizen of the United States, residing in Hartford, in the county of Hartford and 5 State of Connecticut, have invented certain new and useful Improvements in Type-Writing Machines, of which the following is a specification.

This invention relates to the case-shift 10 mechanism of typewriting machines, and particularly to keys which lock and unlock the case-shift mechanism.

In the Underwood typewriting machine, to which my improvements are illustrated 15 as applied, a shift-key is provided at the left-hand side of the keyboard, for the usual purpose of shifting the mechanism to capital printing position; and at the right-hand side of the keyboard, it is customary to provide a similar shift-key, which upon being 20 depressed, will not only shift the mechanism to capital printing position, but will also lock it in such position; a release of said lock being effected by depressing the shift-key at 25 the left-hand-side of the keyboard.

It is found desirable in practice, that there should be not only a key at the left, but also one at the right of the keyboard for effecting a temporary shift of the mechanism to 30 capital printing position, so that the operator may depress, by either his left hand or his right hand, a capital shift-key, and so that upon releasing either of said keys, the mechanism will shift back to its normal 35 position.

The object of this present invention is to provide for the purposes mentioned, a mechanism, not only simple and inexpensive; but also extremely compact; adaptable for use 40 in connection with existing machines with little or no change in the standard parts thereof; neat, in that the operating connections thereof do not encumber the plainly visible parts of the keyboard or key levers; 45 and reliable in that it is certain in operation; does not become uncertain by reason of wear, and requires no delicate shaping and fitting to the parts of the machine with which it is to coöperate.

According to the present improvements, the left-hand shift-key serves for temporarily shifting and also for releasing the platen when it has been locked up. The right-hand shift-key is mounted on a platen-

shifting lever which is used for temporary 55 shifting. Upon the right-hand key lever is a pin or projection, and pivotally mounted upon the frame of the machine is the spring-pressed latch heretofore common to Underwood typewriting machines, the office of 60 which is to catch over the pin or projection on the right-hand key lever to lock down the right-hand shift-key when the latter is depressed; but mounted upon the right-hand key lever is a foil or trip which normally 65 disables the latch, so that it is prevented from catching over the pin. A spring retains this trip in normal position, so that whenever the right-hand shift-key is depressed, the latch is unable to catch over the 70 pin.

To make it possible to lock down the right-hand shift key, there is provided a separate key which is mounted upon the trip to lift the same to ineffective position so that 75 it cannot restrain the latch or lock from catching over the pin on said shift-key lever. This trip, which may be in the form of a lever arm, is capable of limited movement upon the main shift-key lever; serving in its 80 normal, depressed position to render the latch ineffective, and also serving when lifted by depression of a finger key to release the latch to enable it to catch over the pin. The key for this trip also serves to shift the 85 platen. From this, it results that the left-hand key lever may be used for temporary shifting of the platen, and that the right-hand key lever may be employed for the same purpose, and that the trip key may be 90 operated for shifting the platen and locking the same in its shifted position.

The lock or latch for the shift lever may be of the identical style and mounting common in the Underwood typewriting machine; that is to say, may be an upstanding one-armed spring-controlled hook. To adapt the present invention to use in connection with such a latch, the lever which carries the foil or stop, (for interposition 100 in the path of the hook when a temporary shift, only, of the platen is desired) is of novel construction in that it is pivoted at an intermediate point thereof to the right-hand shift lever so that depression of the 105 lock key causes the stop or foil controlled thereby, to be lifted above and out of the path of a coöperating pin or shoulder on the

latch arm when the lock is to be rendered operative; and so that, although the stop or foil is so lifted, the lock key itself, is depressed in the usual manner to cause the foil-carrying lever, as soon as it sets the foil, to pick up, and carry with it, the shift lever on which it is mounted. The lock lever is pivoted to the shift lever at a point of the latter sufficiently removed from the front of the machine to cause it to be substantially concealed from front view, and it is so constructed and positioned as to be free from injury and interference. In mechanism constructed according to the present invention, the pin or detent on the shift lever, which cooperates with the latch, may also serve not only as a means for camming back the latch to permit the latch to pass the pin for engagement over the same; but may serve as a stop which, by coöperation with the foil or interponent, determines the normal position of the foil lever on the shift lever; and may also serve as a stop, to limit the throw of the lock key lever on the shift lever when the lock key is depressed, thereafter causing the two levers to move as a unit in the shifting operation.

The latch may be released by the means usual in the Underwood typewriting machine, a pin upon the left-hand key lever engaging a cam, and the latter fixed on a rock shaft which extends across the machine, and carries the latch heretofore mentioned, whereby said latch is rocked away and releases the right-hand shift-key lever, so that the same returns to normal position together with the platen.

Thus by a simple provision, the operator is enabled to shift the platen temporarily and quickly up or down, with either the right or left hand, while at any time he may rock the platen up for writing a line of capitals, and release the same by the usual key.

Other features and advantages will hereinafter appear.

In the accompanying drawing,

Figure 1 is a front perspective elevation showing a portion of a typewriter carriage, the platen frame, and mechanism with operating keys for shifting the platen vertically.

Fig. 2 is a side elevation of the parts shown in Fig. 1, the platen being in upper-case position, and the shifting mechanism being locked.

Fig. 3 is a fragmentary view in side elevation of one of the shift-keys with the locking key and lock or latch in the position assumed when the shift key is depressed for temporary shift to upper-case position.

Fig. 4 is a fragmentary view in side perspective of the parts shown in Fig. 3, together with the left-hand shift key and the mechanism controlled thereby for unlocking

the platen; the parts being shown in the position assumed at the moment of the release of the platen by the lock or latch.

The operating parts of an Underwood typewriting machine used in connection with the present invention, include the carriage 1, of which a portion only is shown, the platen frame 2, the platen 3 mounted thereon, and the swinging rail 4, supported by brackets 5 mounted on a rock shaft 6, which is journaled in the main frame 7 of the machine. The rail 4 supports the platen frame by means of a roller 8 which rides along the rail as the platen has its letter-feed movement. The rail with the platen is shifted by means of vertical extensions 9 and 10 on the shift levers 11 and 12 respectively; the platen frame being guided in its shifting movement by arms 14 on a rock shaft 13 mounted in the carriage frame.

The key levers 11 and 12, which are fulcrumed on the shaft 15, are held normally elevated as by springs 16, and are provided at their forward ends with the usual keys 17 and 18, one shift-key being at each side of the keyboard.

Either key 17 or 18 may be used to shift the platen to upper-case position for the writing of capitals or other upper-case characters. In the present invention, however, the platen is not locked in upper-case position by depression of either of these keys; whichever of these two keys is operated must be held depressed by the operator, and upon its release, the platen assumes its normal or lower-case position. The advantage of this feature is that occasion for temporary shift may occur when one or the other of the operator's hands may be more conveniently used for actuating the shift lever.

One of the shift levers, however, to wit, lever 11, is provided with means whereby it may at will be locked in upper-case position for permanent or sustained use in that position. This locking means is normally inoperative; that is to say, is inoperative when the shift lever 11 is actuated by its key 17. For operating the lever 11 when the platen is to be locked in upper-case position, the lever 11 carries a second key 19. The key 19 is directly mounted on a short lever 20, pivoted at 21 to the shift lever 11. A leaf spring 22 attached to the shift lever 11' and bearing on the locking lever 20, normally holds the latter lever in Fig. 1 position, with a lug or stop 23, formed by a turned-over portion of said locking lever, in the shape of a gooseneck, bearing against a projecting detent or shoulder, here shown as a pin 24, on the shift lever. As indicated in Fig. 2, depression of the key 19 first rocks the lever 20 around its pivot 21 on the shift lever 11, against the action of the spring 22, until a tooth or shoulder 25 on the lever 20 strikes

the pin 24, and thus determines the relative movement of the two levers; after which, further depression of the key 19 causes the lever 11, which is now interlocked with the lever 20, to be depressed to throw the platen to upper-case position, as if operated by the key 17, except that when the key 19 is operated the platen is locked in its upper-case position.

- 10 The platen is locked in upper-case position by a lock or latch 26 in the form of a one-armed hook fast to a rock shaft 27, which is journaled in the main frame of the machine. This latch has a cam surface 28, 15 which, upon operation of the shift lever 11 by the key 17, is engaged by the pin or detent 24 and forced outward to Fig. 3 position. A spring 29, through connections presently to be described, tends to throw the lock 20 26 to normal, or Fig. 1 position, and therefore tends to cause it, upon sufficient depression of the shift lever 11 to snap over the pin 24, thus locking the shift lever and platen in upper-case position. This part of 25 the locking mechanism has been commonly used in Underwood typewriting machines.

To prevent this locking action at times when the shift lever 11 is to be operated by key 17 for a temporary shift only of the 30 platen, the gooseneck 23 on the lever 20, upon depression of the lever 11, and after the backward swing of the hook 26, interposes itself in Fig. 3 position behind a stop pin 30 carried by the hook 26, thus preventing 35 the latter from being snapped over the lock pin 24 by the spring 29 after it has been cammed back by the pin 24. When the key 17 is released to permit the platen to return to lower case position, the gooseneck lug or 40 stop 23, by reason of its length, continues to be interposed in the path of the lock-retaining pin 30 until the lock-pin 24 is itself elevated into the path of the cam surface 28 on the hook; the parts finally returning to 45 Fig. 1 position.

When, however, the shift lever 11 is operated by the key 19, as above described, its preliminary movement on its pivot 21, relative to the shift lever, causes the lug or stop 50 23 to be lifted, so that at the time the shoulder 25 on the foil lever 20 strikes the pin 24, for movement of the levers 11 and 20 as a unit, the interponent 23 (see Fig. 2) has been elevated to a position such that it cannot 55 obstruct the movement of the lock 26 to locking position when the pin 24 passes from the cam surface 28. In Fig. 2 the parts are shown with the platen locked in upper case position.

60 To release the right-hand shift lever 11 from the hook 26, the latter is rocked by the left-hand shift lever 12 to Fig. 4 position by means heretofore common in Underwood typewriting machines. The shift lever 12 carries a pin 32, adapted upon depression of

the key 18, to engage a cam surface 33 on an arm or plate 34 fast to the rock shaft 27, thereby rocking the shaft 27 in the direction of the arrow, Fig. 4, until the pin 24 is freed from the hook 26; whereupon the 70 springs 16 and the weight of the platen return the parts to lower case position. When the key 18 is released, the spring 29 rocks the shaft 27 to bring the hook 26 to Fig. 1 position. Any suitable spring attachment 75 may be used for turning the rock shaft 27. In the form of the invention shown in the drawing, the spring connections consist of a lever 35 pivoted to the frame at 36 and having a finger 37 to bear against an arm or 80 cam 38 which is integral with the arm or plate 34 by means of which the lock is released. The spring 29 is shown as a coil spring on the pivot 36 of the lever 35, bearing at 39 on the lever 35, and at its other end 85 secured to the frame.

The lever 35 serves its usual function of steadyng the left-hand side of the platen when the latter is in upper-case position. For this purpose it has at its rear, two connected vertical slots 40 and 41. In Fig. 1, or lower-case position, a pin 42 on an extension 43 of one of the platen-holding brackets 5 is interlocked in the slot 40. When a shift lever is operated, and the rock 95 shaft 27 turned by pin 24 or pin 32, acting on cam 28 or cam 33, respectively, the rear of lever 35 is lifted by means of cam 38 and finger 37 to bring the pin 42 to the base of the slot 40; and, as the platen frame is 100 swung forward and upward, the pin 42 passes to Fig. 2 position in the slot 41 to steady and hold the left-hand side of the platen frame.

Variations may be resorted to within the 105 scope of the invention, and portions of the improvements may be used without others.

Having thus described my invention, I claim:

1. In a typewriting machine, the combination with a shiftable platen, of a shift lever, a lock therefor, means for automatically shifting said lock to a predetermined position at each actuation of the shift lever, a stop having a normal effective position on the shift lever such that actuation of the latter for a temporary shift of the platen causes the stop to be carried from a position out of the path of the lock to one in which it is in said path, so as to prevent operation of said lock after having been so shifted, means for moving the stop on the shift lever to an ineffective position from which it cannot, by operation of the shift lever, be brought to its position in the path of the lock, and means for throwing the lock, for sustained shift of the platen, when the shift lever is operated with the stop thereon in ineffective position.
2. In a typewriting machine, the com- 130

- 4
 bination with a shiftable platen, of a lever
 5 depressible to shift the platen, a lock therefor, means for automatically shifting said
 lock to a predetermined position at each
 10 actuation of the shift lever, a stop having a
 normal effective position on the shift lever
 such that actuation of the latter for a tem-
 porary shift of the platen causes the stop
 to be carried from a position out of the
 15 path of the lock to one in which it is in
 said path, so as to prevent operation of said
 lock after having been so shifted, means for
 lifting the stop on the shift lever from its
 20 normal position to an ineffective position
 from which it cannot, by operation of the
 shift lever, be brought to its position in the
 path of the lock, and means for throwing the
 lock, for sustained shift of the platen,
 25 when the shift lever is operated with the
 stop thereon in ineffective position.
 3. In a typewriting machine, the com-
 bination with a shiftable platen, of a shift
 30 lever, a lock therefor, means for automatic-
 ally shifting said lock to a predetermined
 position at each actuation of the shift lever,
 a stop-carrying arm pivoted to the shift
 35 lever and normally held in such angular
 position thereon that actuation of the shift
 lever, for a temporary shift of the platen,
 causes the stop on said arm to move from
 40 its normal position to a position in which
 it is interposed in the path of the lock,
 after said lock has been so shifted, means
 for moving said arm on its pivot in the op-
 45 posite direction to cause the stop thereon to
 be held where movement of the shift lever
 cannot bring it to the path of the lock, and
 means for throwing the lock, for sustained
 50 shift of the platen, when the shift lever is
 operated with the stop thereon in ineffective
 position.
 4. In a typewriting machine, the com-
 bination with a shiftable platen, of a shift
 55 lever, a lock therefor, means for automatic-
 ally shifting said lock to a predetermined
 position at each actuation of the shift lever,
 a stop-carrying arm pivoted to the shift
 60 lever, a spring for normally holding said
 arm in such angular position on the shift
 lever, that actuation of the shift lever, for
 a temporary shift of the platen, causes the
 65 stop on said arm to move from its normal
 position to a position in which it is inter-
 posed in the path of the lock after said lock
 has been so shifted, means for moving said
 70 arm on its pivot in the opposite direction to
 cause the stop thereon to be held where
 movement of the shift lever cannot bring
 it to the path of the lock, and means for
 throwing the lock, for sustained shift of the
 75 platen, when the shift lever is operated with
 the stop thereon in ineffective position.
 5. In a typewriting machine, the com-
 bination with a shiftable platen, of a shift
 80 lever, a detent on said lever, a spring latch
 adapted to engage said detent to lock the
 shift lever when the latter is shifted, said
 85 detent acting to cam back the latch during
 the shifting operation until the latch can
 snap into interlocking engagement with the
 detent, an arm, with a stop thereon, pivoted
 90 on the shift lever and normally held in an
 angular position to cause the stop to be in-
 terposed in the path of the latch after the
 latter has been cammed back, thereby pre-
 95 venting locking of the shift lever when the
 same is actuated for temporary shift of the
 platen, and means for rocking the stop-
 carrying arm reversely to the direction in
 which the shift lever is moved, to prevent
 100 the interposition of the stop in the path of
 the latch when the shift lever is operated
 for a sustained shift of the platen.
 6. In a typewriting machine, the com-
 bination with a shiftable platen, of a shift
 105 lever, a detent on said lever, a spring latch
 adapted to engage said detent to lock the
 shift lever when the latter is shifted, said
 110 detent acting to cam back the latch during
 the shifting operation until the latch can
 snap into interlocking engagement with the
 detent, an offset on the latch, an arm,
 115 with a stop thereon, pivoted on the shift
 lever and normally held in an angular pos-
 120 sition to cause the stop to be interposed in
 the path of the offset on the latch after the
 latter has been cammed back, thereby pre-
 venting locking of the shift lever when the
 125 same is actuated for temporary shift of the
 platen, and means for rocking the stop-
 carrying arm reversely to the direction in
 which the shift lever is moved, to prevent
 the interposition of the stop in the path of
 130 the offset on the latch when the shift lever
 is operated for a sustained shift of the
 platen.
 7. In a typewriting machine, the com-
 bination with a shiftable platen, of a shift
 135 lever, a detent on said lever, a spring latch
 adapted to engage said detent to lock the
 shift lever when the latter is shifted, said
 140 detent acting to cam back the latch during
 the shifting operation until the latch can
 snap into interlocking engagement with the
 detent, an offset on the latch, an arm, with a
 145 stop thereon, pivoted on the shift lever and
 normally held in an angular position to
 cause the stop to be interposed in the path
 of the offset on the latch after the latter has
 been cammed back, thereby preventing lock-
 150 ing of the shift lever when the same is actuated
 for temporary shift of the platen, and
 means for rocking the stop-carrying arm to
 prevent any interposition of the stop in the
 path of the offset on the latch when the shift
 155 lever is operated for a sustained shift of the
 platen.
 8. In a typewriting machine, the com-
 bination with a shiftable platen, of a shift
 160 lever, a detent on said lever, a spring latch

adapted to engage said detent to lock the shift lever when the latter is shifted, said detent acting to cam back the latch during the shifting operation until the latch can snap into interlocking engagement with the 5 detent, an arm, with a stop thereon, pivoted on the shift lever and normally held in an angular position to cause the stop to be interposed in the path of the latch after the latter has been cammed back, thereby preventing locking of the shift lever when the same is actuated for temporary shift of the platen, a key for rocking the stop-carrying arm reversely to the direction in which the 10 shift lever is moved, to prevent the interposition of the stop in the path of the latch when the shift lever is operated for a sustained shift of the platen, and a shoulder on the stop-carrying arm, which when said arm is rocked as aforesaid, engages the shift lever so that the latter may be operated by means of said key.

9. In a typewriting machine, the combination with a shiftable platen, of a shift lever, a detent on said lever, a spring latch adapted to engage said detent to lock the shift lever when the latter is shifted, an arm, with a stop thereon, pivoted on the shift lever and normally held in an angular position to cause the stop to be interposed in the path of the latch when the shift lever is actuated for temporary shift of the platen, means for rocking the stop-carrying arm to prevent the interposition of the stop in the 25 path of the latch when the shift lever is operated for a sustained shift of the platen, and means for holding said interposed stop against said detent on the shift lever to determine the normal position of said rock- 30 arm.

10. In a typewriting machine, the combination with a shiftable platen, of a shift lever, a detent on said lever, a spring latch adapted to engage said detent to lock the shift lever when the latter is shifted, an arm, with a stop thereon, pivoted on the shift lever and normally held in an angular position to cause the stop to be interposed in the path of the latch when the shift lever is actuated for temporary shift of the platen, means for rocking the stop-carrying arm to prevent the interposition of the stop in the path of the latch when the shift lever is operated for a sustained shift of the platen, and a spring for holding said interposed stop against said detent on the shift lever to determine the normal position of said rock- 50 arm.

11. In a typewriting machine, the combination with a shiftable platen, of a shift lever, a lock therefor, a stop-carrying arm pivoted to the shift lever and normally held in such angular position thereon that actuation of the shift lever, for a temporary shift 60 of the platen, causes the stop on said arm to

be interposed in the path of the lock, means for moving said arm on its pivot in the opposite direction to cause the stop thereon to be held where movement of the shift lever cannot bring it to the path of the lock, means for throwing the lock, for sustained shift of the platen, when the shift lever is operated with the stop thereon in ineffective position, a second shift lever, and means operated thereby to disengage the lock from the first 70 mentioned-shift lever.

12. In a typewriting machine, the combination with a shiftable platen, of a shift lever, a lock therefor, a stop-carrying arm pivoted to the shift lever and normally held in such angular position thereon that actuation of the shift lever, for a temporary shift of the platen, causes the stop on said arm to be interposed in the path of the lock, means for moving said arm on its pivot in the opposite direction to cause the stop thereon to be held where movement of the shift lever cannot bring it to the path of the lock, means for throwing the lock, for sustained shift of the platen, when the shift lever is operated with the stop thereon in ineffective position, a rock shaft to which said lock is secured, a cam secured to said shaft, a second shift lever, and means thereon for engaging said cam to rock said shaft to disengage the lock 80 from the first-mentioned shift lever.

13. In a typewriting machine, the combination with a shiftable platen, of a shift lever, a lock therefor, means for automatically shifting said lock to a predetermined position at each activation of the shift lever, a second lever pivoted at an intermediate point thereof to said shift lever, a key carried by one arm of said second lever, a stop carried by the other arm of said second lever, means for normally holding said stop-carrying lever in such angular position on the shift lever that operation of the latter to effect temporary shift of the platen causes said stop to be interposed in the path 100 of the lock after said lock has been so shifted, so as to render the lock inoperative, means whereby the stop-carrying lever may be held in driving connection with the shift lever in such angular position thereon as 105 to withhold the stop from the path of the lock when the shift lever is operated for a sustained shift of the platen, and means for throwing the lock when the stop is so withheld from the path thereof.

14. In a typewriting machine, the combination with a shiftable platen, of a shift lever, a lock therefor, means for automatically shifting said lock to a predetermined position at each activation of the shift lever, a second lever pivoted at an intermediate point thereof to said shift lever, a key carried by one arm of said second lever, a stop carried by the other arm of said second lever, means for normally holding said stop- 115 120 125 130

carrying lever in such angular position on the shift lever that operation of the latter to effect temporary shift of the platen causes said stop to be interposed in the path of the lock after said lock has been so shifted, so as to render the lock inoperative, a shoulder on the stop-carrying lever to engage said shift lever when said key is depressed so that by means of said key both levers may be moved as a unit, with the stop-carrying lever in such angular position on the shift lever as to withhold the stop from the path of the lock, and means for throwing the lock when the stop is withheld from the path thereof, 15 for a sustained shift of the platen.

16. In a typewriting machine, the combination with a shiftable platen, of a shift lever, a lock therefor, means for automatically shifting said lock to a predetermined position at each actuation of the shift lever, a second lever pivoted at an intermediate point thereof to said shift lever, a key carried by one arm of said second lever, a stop carried by the other arm of said second lever, a projection on the shift lever, a spring for normally holding said stop-carrying lever against said projection in such angular position on the shift lever that operation of the latter to effect temporary shift of the platen causes said stop to be interposed in the path of the lock after said lock has been so shifted, so as to render the lock inoperative, means whereby the stop-carrying lever may be held in driving connection with the shift lever in such angular position thereon as to withhold the stop from the path of the lock when the shift lever is operated for a sustained shift of the platen, and means for throwing the lock 40 when the stop is so withheld from the path thereof.

17. In a typewriting machine, the combination with a shiftable platen, of a shift lever, a detent on said lever, a spring latch to engage said detent to lock the shift lever when the latter is shifted, a second lever pivoted at an intermediate point thereof to said shift lever, a key carried by one arm of said second lever, a stop carried by the other arm of said second lever, a spring for normally holding said stop against said detent in such angular position on the shift lever that operation of the latter to effect temporary shift of the platen causes said stop to be interposed in the path of the latch to render the latch inoperative, and means whereby the stop-carrying lever may be held in driving connection with the shift lever in such angular position thereon, as to withhold the stop from the path of the latch when the shift lever is operated for a sustained shift of the platen.

18. In a typewriting machine, the combination with a shiftable platen, of a shift lever, a detent on said lever, a spring latch to engage and lock the shift lever, when the latter is operated for a sustained shift of the platen, means for automatically shifting said hook to a predetermined position at each actuation of the shift lever, a stop on the shift lever normally positioned thereon to be interposed in the path of the spring hook when the shift lever is operated for temporary shift of the platen, so as to prevent operation of said hook after having been so shifted, and means for moving said stop relatively to the shift lever to render the stop ineffective when the shift lever is operated for a sustained shift of the platen.

19. In a typewriting machine, the combination with a shiftable platen, of a shift lever, a key carried by one arm of said second lever, a stop carried by the other arm of said second lever, a spring for normally holding said stop against said detent in such angular position on the shift lever that operation of the latter to effect temporary shift of the platen causes said stop to be interposed in the path of the latch to render the latch inoperative, and a shoulder on the stop-carrying lever to engage the detent on the shift lever when said key is depressed, so that, by means of said key, both levers may be moved as a unit, with the stop-carrying lever in such angular position on the shift lever as to withhold the stop from the path of the latch.

20. In a typewriting machine, the combination with a shiftable platen, of a shift lever, a detent on said lever, a spring latch to engage said detent to lock the shift lever when the latter is shifted, said detent acting to cam back the latch during the shifting operation until the latch can snap into interlocking engagement with the detent, a second lever pivoted at an intermediate point thereof to said shift lever, a key carried by one arm of said second lever, a stop carried by the other arm of said second lever, a spring for normally holding said stop against said detent in such angular position on the shift lever that operation of the latter to effect temporary shift of the platen causes said stop to be interposed in the path of the latch to render the latch inoperative, and means whereby the stop-carrying lever may be held in driving connection with the shift lever in such angular position thereon as to withhold the stop from the path of the latch when the shift lever is operated for a sustained shift of the platen.

21. In a typewriting machine, the combination with a shiftable platen, of a shift lever, a one-armed pivoted spring hook to engage and lock the shift lever, when the latter is operated for a sustained shift of the platen, means for automatically shifting said hook to a predetermined position at each actuation of the shift lever, a stop on the shift lever normally positioned thereon to be interposed in the path of the spring hook when the shift lever is operated for temporary shift of the platen, so as to prevent operation of said hook after having been so shifted, and means for moving said stop relatively to the shift lever to render the stop ineffective when the shift lever is operated for a sustained shift of the platen.

22. In a typewriting machine, the combination with a shiftable platen, of a shift lever, a one-armed pivoted spring hook to engage and lock the shift lever when the latter is operated for a sustained shift of the platen.

platen, means for automatically shifting said hook to a predetermined position at each actuation of the shift lever, an arm pivoted to the shift lever having a stop thereon, means for holding said arm normally at such an angle on the shift lever that operation of the latter causes the stop to be interposed in the path of the spring hook after said hook has been so shifted, so as to prevent locking movement thereof, and means whereby the stop-carrying arm may be rocked on the shift lever so as not to be interposed in the path of the hook when the shift lever is operated, thereby permitting the shift lever to be locked for a sustained shift of the platen.

21. In a typewriting machine, the combination with a shiftable platen, of a shift lever, a one-armed pivoted hook to engage and lock the shift lever, when the latter is operated for a sustained shift of the platen, means for automatically shifting said hook to a predetermined position at each actuation of the shift lever, a stop on the shift lever normally positioned thereon to be interposed in the path of the hook when the shift lever is operated for temporary shift of the platen, so as to prevent operation of said hook after having been so shifted, means for moving said stop relatively to the shift lever to render the stop ineffective when the shift lever is operated for a sustained shift of the platen, and means for throwing the hook when said shift lever is operated with said stop in ineffective position thereon.

22. In a typewriting machine, the combination with a shiftable platen, of a shift lever, a detent on the shift lever, a one-armed pivoted spring hook for engagement with said detent to lock the shift lever when the latter is operated for a sustained shift of the platen, said detent acting to cam back the hook during the shifting operation until the hook can snap into interlocking engagement with the detent, an arm pivoted to the shift lever having a stop thereon, means for holding said arm normally at such an angle on the shift lever that operation of the latter causes the stop to be interposed in the path of the spring hook to prevent locking movement thereof, and means whereby the stop-carrying arm may be rocked on the shift lever so as not to be interposed in the path of the hook when the shift lever is operated, thereby permitting the shift lever to be locked for a sustained shift of the platen.

23. In a typewriting machine, the combination, with a shiftable platen; of a shift lever having a lateral projection thereon; a latch engageable with said projection to lock the shift lever when the latter is actuated for a sustained shift of the platen, said projection arranged to move said latch

into a predetermined position at each actuation of the shift lever; an arm pivoted to the shift lever and provided with a stop; a pin on said latch adapted for engagement by said stop when said latch has been moved 70 into said position by said projection to prevent operation of the latch; and means for rocking said arm so as to carry said stop out of range of said pin when the shift lever is actuated for a sustained shift of the 75 platen.

24. In a typewriting machine, the combination, with a shiftable platen; of a shift lever having a lateral projection thereon; a latch engageable with said projection to 80 lock the shift lever when the latter is actuated for a sustained shift of the platen, said projection arranged to move said latch into a predetermined position at each actuation of the shift lever; an arm pivoted to 85 the shift lever at an intermediate point thereof and provided at one end with a stop and at the other end with an operating key; and a pin on said latch adapted to be positioned in front of said stop for engagement therewith, when said latch has been moved into said predetermined position by said projection, so as to prevent operation of the latch, said key arranged to rock said arm so as to carry said stop out of 90 range of said pin when the shift lever is actuated for a sustained shift of the platen.

25. In a typewriting machine, the combination, with a shiftable platen; of a shift lever having a projection thereon; a latch 100 engageable with said projection to lock the shift lever when the latter is actuated for a sustained shift of the platen; an arm pivoted to the shift lever and provided with a pair of spaced stops or shoulders between 105 which said projection has play, one of said stops arranged to prevent engagement of said projection by said latch when the shift lever is actuated for a temporary shift of the platen; and means for rocking said arm 110 to render said stop ineffective for such preventing action when the shift lever is actuated for a sustained shift of the platen, and to engage the other stop with said projection to enable subsequent downward movement of said arm and said shift lever as a unit.

26. In a typewriting machine, the combination, with a shiftable platen; of a shift lever having a projection thereon; a latch 120 engageable with said projection to lock the shift lever when the latter is actuated for a sustained shift of the platen; an arm pivoted to the shift lever and provided with spaced upper and lower stops or shoulders between 125 which said projection has play; a spring arranged to hold the upper stop against said projection, so as to determine the normal position of said arm; said upper stop arranged to prevent engagement of said pro- 130

jection by said latch when the shift lever is actuated for a temporary shift of the platen; and means for rocking said arm to render said upper stop ineffective for such preventing action when the shift lever is actuated for a sustained shift of the platen, and to engage the lower stop with said projection

to enable subsequent downward movement of said arm and said shift lever as a unit.

WILLIAM F. HELMOND.
